PISTON

Application filed February 10, 1928. Serial No. 253,409.

This invention relates to new and useful improvements in pistons generally, although the invention is particularly intended for use in connection with pistons employed in engines of the explosive type.

5 It is a well known fact that pistons become worn during extensive use and as a result piston "slapping" becomes very noticeable. The wearing of the piston also causes oil to leak past the rings.

10 Among the several objects of our invention are to provide a piston with means for expanding the piston skirt for the purpose of taking up wear and thereby not only avoid the "slapping" but also prevent the undue 15 leakage of oil past the rings; to provide an expanding device for the purpose set forth which can be readily adjusted from the head end of the piston and from a point exterior 20 thereof without the necessity of disconnecting and removing the piston from its associated cylinder, and to provide such an expanding device and actuating means therefor which are of simple construction, which 25 may be readily applied to any piston, and which will remain in adjusted position.

With these and other objects in view which will more fully appear, the nature of the invention will be more clearly understood by 30 following the description, the appended claims, and the several views illustrated in the accompanying drawings.

In the drawings:

Figure 1 is a side elevation of a piston embodying our invention,

35 Figure 2 is a fragmentary sectional view taken on the line 2-2 of Figure 1,

Figure 3 is a partial top plan view and cross section taken on the line 3-3 of Figure 1,

40 Figure 4 is a longitudinal sectional view through the piston,

Figure 5 is a perspective view showing the expanding device and actuating means in disassociated relation,

45 Figure 6 is a detail longitudinal sectional view through the piston showing another embodiment of our invention, and

Figure 7 is a perspective view similar to 50 Figure 5 but showing the modified construction of Figure 6.

Like reference numerals designate corresponding parts throughout the several figures of the drawings.

Referring to the accompanying drawings, we have illustrated a piston 10 having an integral head 11 and skirt 12 which is longitudinally slotted as at 13. The skirt 12 is also provided with spaced transverse webs 19 and 21 which are located on opposite sides of the slot 13.

55 The expanding device is indicated generally at 14, and this device, which is shown in Figs. 1 to 5 inclusive, comprises a rod 15 having one end threaded, as at 16, and the other end formed with a longitudinal slot 17. This 60 rod is located on the side of the piston axis adjacent the slot 13 and extends in a plane at right angles to the webs 19 and 21. The threaded end 16 of the rod is engaged with a threaded opening 18 formed in the web 19 and the slotted end of the rod is freely mounted in an opening 20 formed in the web 21. The slot 17 is of a length sufficient to extend to a point spaced from the web 21 so as to permit 65 a wedge 22 to be inserted within the slot 17 70 between the web 21 and the end wall or shoulder 17^a of the slot. The wedge 22 is formed with a threaded shank 23 which extends upwardly towards the head 11 of the piston. Formed in the head 11 directly above 75 the shank 23 is an opening 26 for receiving the upper end of an actuating element 24 which in this instance is shown as a sleeve. The sleeve is interiorly threaded so as to permit the lower end thereof to engage the threaded shank 23. 80

85 The outer face of the sleeve is devoid of threads and is freely positioned for rotation within the opening 26. The sleeve is formed with a shoulder 25 which bears against the under face of the head 11. In order to turn the sleeve 24 and thereby move the wedge 22 to expand the skirt 12, we have formed the upper end of the sleeve 24 into a shape for receiving a tool. In this instance, the upper end 90 of the sleeve is formed with a transversely disposed slot 27 for receiving a screw driver. It is desirable to close the opening 26 so as to prevent escape of gas from the associated cylinder, and for this purpose we have employed a closure 28 which is in the nature of a 95 100

screw, the shank thereof having threaded engagement with the upper end of the threaded sleeve 24, and the head thereof being under beveled to fit a correspondingly shaped seat formed around the outer end of the opening 5 26.

In the modified construction shown in Figs. 6 and 7, we have employed the same rod 15, wedge 22, threaded shank 23 and closure screw 28. The only change lies in the construction of the actuating element or sleeve which in this instance is designated at 24^a. This modified sleeve is exteriorly threaded as well as interiorly threaded, the exterior 10 thread permitting the sleeve to be engaged with the threaded opening 26^a formed in the head 11.

From the foregoing, it will be observed that it is only necessary in applying our invention 15 to an ordinary piston to form three openings 18, 20 and 26, the first two openings being in the webs 19 and 21 respectively, and the third opening being in the head 11.

It is of course to be understood that the details of structure and arrangements of parts 20 may be variously changed and modified without departing from the spirit and scope of our invention.

We claim:—

1. A piston comprising an integral shell portion having a slot extending lengthwise therethrough for a part of its length, and means for expanding said shell portion to take up for wear, said means consisting in a 25 horizontally mounted rod having one end thereof threaded into one wall of the piston, a transversely extending tapered wedge engageable with the other end of the rod and with the shell, and means for causing the 30 relative movement between the wedge and said transversely extending pin.

2. A device of the character described comprising a piston having a pair of oppositely disposed web portions, a transversely disposed rod extending through the web portions, a vertically extending wedge having a 35 reduced threaded portion and adapted for engagement with said rod, and a sleeve in engagement with said reduced end, said sleeve being operable from the end of the piston.

3. A device of the character described comprising a piston having a pair of oppositely disposed web portions, a transversely disposed rod extending through the web portions, a vertically extending wedge having a 40 reduced threaded portion and adapted for engagement with said rod, a sleeve in engagement with said reduced end, said sleeve being operable from the end of the piston, and a 45 headed screw adapted to engage said sleeve and the adjacent portion of the piston for effecting the locking thereof.

4. The combination of a piston including a head and a longitudinally slotted skirt, and 50 means movable transversely of the head for

expanding said skirt including a device engageable with the skirt on opposite sides of the slot, and actuating means for moving the expanding device and accessible from the exterior of the head.

5. The combination of a piston including a head and a skirt, and means for expanding said skirt including a rod extending across the skirt and having one end fixed thereto, and a wedge cooperating with the other end 70 of the rod and skirt, and actuating means for moving said wedge transversely of the rod.

6. The combination of a piston including a head and a skirt, and means for expanding said skirt including a rod extending across the skirt and having one end fixed thereto, and a wedge cooperating with the other end 75 of the rod and skirt, and actuating means for moving said wedge transversely of the rod comprising a rotatable and endwise movable element engageable with the head and wedge.

7. The combination of a piston including a head and a skirt, and means for expanding said skirt including a rod extending across the skirt and having one end fixed thereto, and a wedge cooperating with the other end 80 of the rod and skirt and provided with a threaded shank extending towards said head, and actuating means for moving said wedge 85 transversely of the rod comprising a sleeve having one end engaging the shank of the wedge and the other end engaging the head of the piston.

8. The combination of a piston including a head and a longitudinally slotted skirt, the latter being formed with an opening, and means for expanding said skirt including a rod extending across the skirt and having one 90 end fixed thereto opposite said opening and having its other end freely mounted within said opening, and a wedge cooperating with the freely mounted end of the rod and with the skirt, and actuating means for moving said wedge transversely of the rod.

9. The combination of a piston including a head and a longitudinally slotted skirt, said head and skirt being each formed with an opening, and means for expanding said skirt including a rod extending across the skirt 95 and having one end fixed thereto opposite the opening in the skirt and having its other end freely mounted within said opening, and a wedge cooperating with the freely mounted end of the rod and with the skirt, and actuating means accessible through the opening in the head for moving said wedge transversely of the rod.

10. The combination of a piston including a head and a longitudinally slotted skirt, said head and skirt being each formed with an opening, and means for expanding said skirt including a rod extending across the skirt 100 and having one end fixed thereto opposite the opening in the skirt and having its other end freely mounted within said opening, and a wedge cooperating with the freely mounted end of the rod and with the skirt, and actuating means accessible through the opening in the head for moving said wedge transversely of the rod.

freely mounted within said opening, and a wedge cooperating with the freely mounted end of the rod and with the skirt, and actuating means for moving the wedge transversely of the rod comprising a rotatable and end-
wise movable element having its inner end en-
gageable with the wedge and its outer end en-
gageable with the head and extending into
the opening of the head, the outer end of the
element being shaped for engagement by a
tool whereby the element may be rotated
from the exterior of the piston.

11. The combination of a piston including
a longitudinally slotted skirt and spaced
transverse webs disposed on opposite sides of
the slot, and means for expanding the skirt
including a rod having one end fixed to one
web, and a wedge cooperating with the other
end of the rod and with the other web, and
actuating means for moving the wedge trans-
versely of the rod.
